UNITED STATES PATENT OFFICE

2,526,369

MECHANICAL ARROW-PROJECTING TOY

Henry A. Kieselhorst, St. Louis, Mo.

Application April 26, 1947, Serial No. 744,123

3 Claims. (Cl. 124—23)

1

The present invention relates generally to amusement devices, and more particularly to a mechanical amusement device of the target type in which a controlled projectile is mechanically ejected towards a target or target area.

An object of the present invention is to provide a novel mechanical amusement device in which a remotely controlled projectile is mechanically ejected towards a target or target area.

Another object is to provide a novel mechanical amusement device which incorporates a maneuverable figure and a remotely controlled projectile holder which is maneuverable in planes both parallel to and vertical to the considered ground surface, providing, in effect, universal movement over a predetermined area of movement.

Another object is to provide a novel mechanical amusement device which is adapted to forcibly eject an arrow, simulated bullet, or the like, towards a target.

Another object is to provide a novel mechanical amusement device which incorporates a maneuverable figure.

Another object is to provide a novel mechanical amusement device which incorporates both a maneuverable projectile holder from which a projectile is adapted to be ejected and at least one movable target.

Another object is to provide a novel mechanical amusement device which incorporates one or more maneuverable projectile holders including release means for each where more than one is employed, which function for simultaneous or successive release of the projectiles as desired.

Another object is to provide a novel mechanical amusement device which incorporates a bow and arrow of miniature or regulation size, as the desire may be, which is adapted to release the arrow towards a target upon the actuation of a provided release device.

Another object is to provide a novel mechanical amusement device which realistically simulates bow and arrow action, and which is accurate enough in the release of an arrow from the body to constitute a device of skill.

Other objects are to provide a novel mechanical amusement device which is sturdy in construction, which is inexpensive to fabricate, which is adapted to serve its intended usage with no more than minimum maintenance for an extended period of time, and which finds wide adaptation as a device of skill for both children and adults.

The foregoing and other objects and ad-

2

vantages are apparent from the following description taken with the accompanying drawing, in which:

Fig. 1 is a side elevational view of a mechanical amusement device formed in accordance with the teachings of the present invention;

Fig. 2 is a view similar to Fig. 1 illustrating the bowstring and arrow engaged in the projectile holder and the several parts of the device 10 in the maximum elevated position;

Fig. 3 is a view similar to Fig. 2, but with the several elements of the device in the maximum depressed position;

Fig. 4 is a horizontal sectional view on the line 15 4—4 of Fig. 1, positions of movement of the device being indicated in broken line;

Fig. 5 is an enlarged vertical sectional view on the line 5—5 of Fig. 1 illustrating trigger linkage details;

Fig. 6 is a vertical sectional view substantially on the line 6—6 of Fig. 1;

Fig. 7 is an enlarged side elevational view of the projectile holder and related parts;

Fig. 8 is an enlarged side elevational view of 20 the projectile holder viewed at 180° to Fig. 7;

Fig. 9 is an enlarged horizontal cross-sectional view on the line 9—9 of Fig. 7 showing the projectile holder in top plan and with an arrow shaft being inserted;

Fig. 10 is an enlarged horizontal cross-sectional view on the line 10—10 of Fig. 7 showing an arrow shaft being inserted;

Fig. 11 is an enlarged horizontal cross-sectional view also taken on the line 10—10 of Fig. 35 7 showing the arrow fully inserted and the bowstring engaged by the lock leaf;

Fig. 12 is an enlarged horizontal cross-sectional view also taken on the line 10—10 of Fig. 40 7 showing the lock leaf in bowstring release position and the arrow leaving the holder under the spring force of the bow member as imparted by the bowstring;

Fig. 13 is an enlarged vertical cross-sectional view on the line 13—13 of Fig. 11;

Fig. 14 is an enlarged vertical cross-sectional view on the line 14—14 of Fig. 7;

Fig. 15 is an enlarged side elevational view, partly in section, of the body member of the projectile holder showing the side against which 50 the lock leaf rests;

Fig. 16 is an enlarged side elevational view, partly in section, of the body of the projectile holder showing the side against which the projectile retainer plate rests;

Fig. 17 is an isometric view of the lock leaf;

Fig. 18 is a side elevational view of an arrow adapted to be used with the present device;

Fig. 19 is an enlarged fragmentary top plan view of the feathered end of the arrow shown in Fig. 18;

Fig. 20 is a diagrammatic view of the present device mounted on a movable support and disposed in relation to a vertical target surface; and

Fig. 21 is a diagrammatic view showing the present device combined with a target which moves as the projectile is being released.

Referring to the drawings more particularly by reference numerals, 25 indicates generally a mechanical amusement device incorporating the concepts of the present invention. To a stationary support 26, which may be a box 26, as shown in Fig. 20, a platform 29, as shown in Fig. 21, or any other type of support, is pivotally secured a member 30 by means of a rivet 31, or the like, extending through vertically spaced extensions 32 of the member 30 and through the support 26 (Figs. 1 and 4). The member 30 also includes laterally spaced extensions 33 between and to which is secured, as by welding 34, a vertically disposed post 35. To the upper end of the post 35 are pivotally connected by a rivet 39 a figure-shaped member 40 and a plate member 41. The plate member 41 is of the shape clearly shown in Figs. 1 and 7 and includes a body portion 42 and a depending arm 43 which terminates in a lateral extension 44. A rivet 45, or the like, extends through the plate 41 at the juncture of the arm 43 and the extension 44 and through a projection 46 of the figure-shaped member 40 and cooperates with the rivet 39 to maintain the figure-shaped member 40 and the plate member 41 in fixed relation to each other. A strap member 47 is pivotally mounted on the rivet 45 at its upper end and at its lower end is pivotally connected by a rivet 48, or the like, to a manipulative handle member 49. The strap member 47 is parallel to the post 35, as is clear from Fig. 1. The lower end of the post 35 is pivotally connected by a rivet 50, or the like, to the free end of the handle member 49, the other end of said handle member 49 terminating in a handle grasp portion 51. Manifestly, as is clear from Figs. 1 through 3, elevation of the hand grasp portion 51 of the handle member 49 about the pivot rivet 50 effects forward tilting of the plate member 41 about the rivet 39 as a pivot point, and downward movement of the hand grasp portion 51 about the pivot rivet 50 effects rearward tilting of the plate member 41 about the pivot rivet 39.

The figure-shaped member 40 may take any configuration, such as that of an Indian, an archer, or the like, and is cut away at 53 for a purpose described below and includes an arm 55 extending forwardly from and above the body portion 42 of the plate member 41. A detached leg portion 54 is secured to the post 35 for movement therewith. A resilient member 56 in the shape of a bow is secured by a clamp 57 of any suitable form to the free end of the arm 55. A bowstring 58, preferably of fine piano wire, is secured to the free ends of the resilient member 56 as by returned end portions 59. An arrow 60 is provided for projection by the resilient member 56 (Figs. 18 and 19) and includes a shaft 61 having feathers 62 adjacent one end. A notch 63 is formed in that end of the shaft 61 adjacent the feathers 62.

A projectile holder 65 is mounted on the body portion 42 of the plate member 41 as by welding

66 (Fig. 7) and includes a body member 67 (Figs. 1 and 6 through 17). The body member 67 is of forked configuration and includes a bight portion 68 and vertically spaced legs 69—70 (Figs. 15 and 16). Through the bight portion 68 is a vertical opening 71 and formed in the front face thereof is a channel 72. Extending vertically through the legs 69 and 70 is a pair of spaced aligned openings 73 and 74.

5 A lock leaf 77 (Fig. 17), including a body portion 78 and spaced flanges 79, is pivotally mounted on the body 67 by means of a vertical non-rotatable pin 80 (Fig. 13) disposed through the openings 74 in the body portion 78 and aligned holes 81 in the flanges 79 and peened over at its ends to secure it in place. The flanges 79 are disposed between the legs 69 and 70 when the lock leaf 77 is in closed or locking position. Each flange 79 includes a side edge portion 82 which slopes away from the body portion 78 and an end edge 83 which is at right angles to the body portion 78 and which intersects the sloping edge portion 82. A coil spring 84 surrounds the pin 80 and has one end 85 anchored thereto (Fig. 13). 20 The other end 86 of the spring 84 extends along the outer surface of the body portion 78 biasing the lock leaf 77 into its closed position, clearly shown in Figs. 10 and 11.

25 A projectile retainer plate 90 is also pivotally mounted on the body member 67 (Figs. 8 and 10 through 14), and includes a flat body portion 91 centrally of which is a channel 92. At one end of the body portion 91 are vertically spaced horizontal ears 93 having aligned apertures. A vertical non-rotatable pin 94 extends through the openings in the ears 93 and through the aligned openings 73 in the body member 67 to pivotally mount the projectile-holding member 90 on the body member 67, as is clear from the drawings. 30 The pin 94 is peened over at the ends to prevent withdrawal. A coil spring 95 surrounds the pin 94 and has one end 96 extending therethrough, the other end 97 thereof being disposed against the outer surface of the body portion 91 to bias the plate 90 towards the body member 67. The body portion 91 is cut away at 98 (Fig. 8) to permit the end 97 of the spring 95 to pass freely into its engaging position.

35 A wide member 100 of the configuration clearly shown in Fig. 7 is pivotally mounted in the vertical opening 71 of the body member 67 and includes a horizontal free end portion 101 and a vertical free end portion 102. As is clear from Figs. 9 through 12, the vertical portion 102 is 40 normally disposed in the channel 72 but may be pivoted clockwise to pivot the lock leaf 77 counter-clockwise about its mounting pin 80. To the end portion 101 is connected the upper end of a generally vertically disposed rod 103, the lower end of said rod 103 extending through an aperture 104 in a bracket 105 (Figs. 1 and 5) secured to the handle member 49 by suitable screws 106, or the like. The lower end of the rod 103 terminates in a right angularly directed portion 108, 45 the free tip of which is flattened and includes an aperture 109. Extending downwardly through the aperture 109 is the angularly disposed end 110 of an elongated trigger rod 111, the angularly disposed end 110 being maintained against removal by a pin 112 (Figs. 4 and 5). The trigger rod 111 includes an offset portion 113 which terminates in the aforesaid portion 110, a main body portion 114 which parallels the handle member 49, and a finger portion 115 (Fig. 1) disposed downwardly from and at right angles to

the main body portion 114. A bracket 116 secured to the handle member 49 by welding, or the like, supports the trigger rod 111 for reciprocating movement and serves as a stop to limit movement to the right, considering Fig. 1. A tension spring 117 anchored by one end 118 to the handle member 49 and by the other end 119 to the trigger rod 111 biases the trigger rod 111 into the position shown in Fig. 1. It is to be noted that the apertures 104 and 109 are large enough to permit the range of angular movement between the rod 103 and trigger rod 111, as is illustrated in Figs. 2 and 3. The same thing is true in respect to the connection of the upper end of the rod 103 with the portion 101 of the member 100.

As is stated above, the figure-shaped member 40 may take any form and may be made of any suitable material, and, since it is contemplated that a strong plastic may be employed, the plate member 41 is used to mount the projectile holder 65. It is to be understood that where a sheet metal silhouette figure is employed, the projectile holder 65 may be secured directly thereto. Stop members to limit transverse and vertical movement of the handle member 49 may be provided if desired.

In Fig. 20, the mechanical amusement device 25 is shown mounted on the box 28 which may be freely movable in respect to the surface 125, or it may be secured thereto. A target screen 126 is provided on which may be placed any suitable targets of paper, or the like, into which the arrow 60 may penetrate or which the arrow may mark for scoring purposes.

In Fig. 21, the device 25 is shown mounted on the platform 29. At the right end of the platform 29 is a log 130 behind which and movable in respect thereto is a rabbit-shaped member 131. Movement of the rabbit-shaped member 131 is effected through the reciprocation of the trigger rod 111. A rod 132 is secured at one end to the trigger rod 111 and at the other end to one leg 133 of a bell crank lever 134, the other end 135 thereof being connected by a pin 136 and slot 137 to a post 138 which extends through the platform 29 and supports the member 131. A V bracket 139 pivotally supports by a pin 140 the bell crank lever 134, the V bracket 139 being secured to the underside of the platform 29. It is to be understood that nonmovable objects, such as additional game figures, may be disposed on the platform 29 for target purposes.

The device 25 is illustrated as incorporating a bow and arrow. However, it is to be understood that the inventive concept includes the use of other projectiles such as the bullet from a gun, or the like, in which case the figure member 40 would be formed to simulate a cowboy, policeman, or the like. When using bullets, darts, spears, and the like, in place of an arrow, the bow shown is replaced by a suitable ejector spring which may be readily located in the body member 67 of the projectile holder 65. It is to be further understood that the projectile holder 65 may be surrounded by a figure, in which case the rod 103 may be formed in two pieces including an upper link portion disposed within such figure to permit bending action.

Operation

It is apparent from the foregoing description taken with the accompanying drawings that the amusement device 25, as illustrated, may be aimed for firing an arrow 60 by manipulating the handle

member 49 in vertical and horizontal planes (Figs. 1 through 4). It is further apparent that an arrow 60 may be released through rearward movement of the trigger rod 111 at any aimed position.

When the projectile holder 65 is empty, the projectile holder plate 90 will be in the position as shown in Fig. 12. To load the holder 65 with an arrow 60, the bowstring 58 of the bow member 56 is engaged by the notch 63 of an arrow 60 and the arrow 60 is slipped into the holder 65 along the channel 92. The arrow 60 is moved to the left, considering Figs. 10 and 11, until the bowstring 58 engages the sloping edge portions 82 to pivot the lock leaf 77 counterclockwise to clear the same and to move into position to the left of the end edges 83, the lock leaf 77 returning to the position shown in Fig. 11 under the influence of the spring 84 as soon as the sloping edge portions 82 are free of engagement by the bowstring 58. Figs. 2 and 3 show an arrow 60 engaged by the holder 65, the lock leaf 77 serving to fully support the arrow 60. The forward end of the arrow 60 is disposed below the arm 55 of the figure member 40 and below the clamp 51 in order to avoid possible undesirable deflections of the arrow 60 by these elements.

Manifestly, when the device 25 is loaded with an arrow 60, as shown in Figs. 2 and 3, the bow member 56 is under tension. To release the arrow 60, it is but necessary to apply finger pressure to the finger portion 115 of the trigger rod 111 to move the trigger rod 111 rearwardly and to therethrough effect pivotal movement of the member 100 to pivot the lock leaf 77 counterclockwise (Fig. 12) to move the edges 83 thereof out of the path of the bowstring 58 to release the latter. The stored up tension of the bow member 56 immediately becomes effective to draw the bowstring 58 to the position of Fig. 1 and to forcibly eject the arrow 60 from the holder 65.

As indicated above, the device 25 may take manifold forms and may be adapted to a number of uses without departing from the inventive concepts. The device 25 finds particular adaptation as a game of skill, as is indicated by Figs. 20 and 21, among other uses.

It is apparent that there has been provided an amusement device which fulfills all the objects and advantages sought therefor.

It is to be understood that the foregoing description and the accompanying drawings have been given by way of illustration and example. It is also to be understood that changes in form of the several parts, substitution of equivalent elements, and rearrangement of parts, which will be readily apparent to one skilled in the art, are contemplated as within the scope of the present invention, which is limited only by the claims which follow.

What is claimed is:

1. In a device of the type described, a support; means pivotally mounting said support for vertical and horizontal movement; and a projectile holder secured to said support, said holder including a body member containing opposed faces and an elongated notch extending inwardly from one end thereof, an elongated ejecting-means retaining member pivotally mounted adjacent one end of the body member, said retaining member including projection means extending into the notch in the body member and a flange-like portion for contact with one face of the body member, spring means urging said flange-like

portion against said one face, a plate-like projectile-retaining member pivotally mounted adjacent the other end of the body member, said projectile-retaining member containing a longitudinally extending groove in the inner face thereof adjacent the notch to receive a projectile, and also containing flange-like portions for contact with the other face of the body member, and spring means urging said flange-like portions against said other face of the body member.

2. In a device of the type described, a bow containing a bowstring; means supporting said bow for vertical and horizontal movement; and means for releasably maintaining an arrow and the bowstring in tensioned position, said last named means including a body member containing opposed faces and an elongated notch extending inwardly from one end thereof, an elongated bowstring retaining member pivotally mounted adjacent one end of the body member, said retaining member including projection means extending into the notch for engagement with the bowstring and a flange-like portion for contact with one face of the body member, spring means urging said flange-like portion against the face of the body member, a plate-like arrow retaining member pivotally mounted adjacent the other end of the body member containing a longitudinally extending groove in the inner face thereof to receive the feathered end of an arrow, and also containing flange-like portions for releasably holding the feathered end of an arrow against the other face of the body member, and spring means urging said flange-like portions against said other face of the body member.

3. A target device, comprising a figure-shaped member; a bow and a bowstring supported by said figure-shaped member; means supporting said member for vertical and horizontal movement; means fastened to said member for releasably maintaining an arrow and bowstring in tensioned position, said last named means including a body member containing opposed faces and an elongated notch extending inwardly from one end thereof, an elongated bowstring retain-

ing member pivotally mounted adjacent one end of the body member, said retaining member including projection means extending into the notch for engagement with the bowstring and a flange-like portion for contact with one face of the body member, spring means urging said flange-like portion against the face of the body member, a plate-like arrow retaining member pivotally mounted adjacent the other end of the body member, said retaining member containing a longitudinally extending groove in the inner face thereof to receive the feathered end of an arrow, and also containing flange-like portions for releasably holding the feathered end of an arrow against the other face of the body member, and spring means urging said flange-like portions against said other face of the body member; and trigger means for pivoting the bowstring retaining member away from the face of the body member to disengage the projection means on the retaining member from the bowstring.
